UNITED STATES PATENT OFFICE

GHOUGAS ZAHRAJIAN, OF SYRACUSE, NEW YORK

DEVICE FOR LOCATING SUNKEN VESSELS

Refile of abandoned application Serial No. 416,941, filed December 23, 1929. This application filed April 16, 1932. Serial No. 605,723.

This invention relates to devices for locating sunken vessels to facilitate raising thereof.

The primary object of the present invention is to provide an improved device of the above kind which may be conveniently arranged upon a submarine or other vessel, and which will, in the event of sinking of the vessel, permit the release of a float or buoyant marker adapted to float on the surface of the water above the vessel to indicate the position of the latter, whereby a grappling device may be lowered and engaged with a further grappling member, fixed on the sunken vessel, to raise the latter.

In carrying out my invention, I arrange in a covered compartment of the vessel a buoyant marker to which is attached a cable which is also attached to and wound upon a drum journaled in the bottom of the compartment. Means are provided for effectively securing the cover of the compartment in closed position so that it may be readily released from the interior of the vessel, to forcibly open the said cover when released, to project the buoyant marker from the compartment when the cover is opened, and to notify the occupants of the vessel when the cable is paying out properly to permit the marker to rise to the surface of the water.

Rigid grappling members are provided on the outside of the vessel adjacent the compartment to facilitate engagement of a cooperating grappling member with one of the same when said cooperating grappling member is lowered from a salvaging vessel at the point where the buoyant marker is found, thereby facilitating raising of the sunken vessel.

The invention consists in the novel form, combination and arrangement of parts hereinafter more fully described, shown in the accompanying drawings, and claimed.

In the drawings:

Figure 1 is a view illustrating the manner of using my device, a grappling member being shown partially lowered adjacent the buoyant marker of a sunken vessel.

Figure 2 is an enlarged fragmentary ver-

tical section through the compartment in which the drum and marker are located.

Figure 3 is a horizontal section on line 3—3 of Figure 2.

Figure 4 is a horizontal section on line 4—4 of Figure 2.

Figure 5 is a horizontal section on line 5—5 of Figure 2.

Figure 6 is a vertical section on line 6—6 of Figure 2.

Figure 7 is a vertical section on line 7—7 of Figure 2, the marker being shown by dotted lines to reveal structural details; and

Figure 8 is a perspective view of the spring hammer which is arranged to strike the bottom of the compartment to notify the occupants of the sunken vessel when the cable pays out to allow the marker to rise to the surface of the water.

Referring in detail to the drawings, 5 indicates a submarine or other vessel whose deck floor 6 is apertured to receive a metallic compartment 7 with the cover 8 thereof disposed substantially flush with said deck floor.

Freely mounted in the upper portion of the compartment 7 so as to be readily displaceable therefrom is a float or buoyant marker 9 having a bottom eye 10, or the like, to which is attached one end of a cable 11. Journaled within and mounted upon the bottom of the compartment 7 is a drum 12 on which the cable 11 is normally wound and attached at its other end.

The float or marking buoy 9 is disposed on a horizontal supporting ring 13 which is yieldably suspended in the compartment 7 by means of helical tension springs 14, and the arrangement is such that when the marker 9 is pressed into the compartment sufficiently to permit closing of the cover 8, the springs 14 are placed under tension. This provides for forcible projection of the marker from the compartment by the springs 14 when the cover 8 is opened and the marker is released.

The cover 8 is hinged at one side to the top of the compartment 7, as at 15, and at the opposite side the cover has a keeper 16 engageable by a swinging latch-hook 17 to hold the cover closed. The latch-hook 17 is carried by a shaft 18 journaled in and extending

through the side of the compartment and a packing box 19 carried by the latter, the outer end of shaft 18 being engageable by a key 20 to permit turning of the same and release of the latch-hook 17 by an authorized person within the sunken vessel.

Mounted in a guide 21 on the inside of the compartment 7 adjacent the latch-hook 17 is a vertically movable rack-bar 22 whose teeth are engaged by a pinion 23 carried by a further shaft 24 similar to shaft 18 and journaled in a like manner in the side of the compartment 7. When the rack-bar 22 is lowered and the cover 8 is closed, the upper end of said rack-bar impinges the under side of said cover, so that when the latch-hook 17 is released and the rack-bar is raised by turning shaft 24, the cover 8 is forcibly started open. The opening of the cover is assisted and completed by means of a spring device 25 consisting of an angular spring member coiled intermediate its ends as at 26 and having one arm attached to the side of the compartment 7 adjacent the hinge 15, the other arm thereof having a free end provided with a roller 27 bearing against and exerting an upward pressure upon the under side of said cover.

A spring hammer 28 is attached at one end 30 to the bottom wall of the compartment 7. This hammer embodies a spring member coiled intermediate its ends as at 29 and having a free arm provided with a lateral terminal extension 30 arranged to be intermittently engaged by a lateral arm 31 on one end of the shaft of drum 12 to intermittently raise and release the free arm of the hammer when the drum 12 is rotated as the cable 11 is paid therefrom. The free arm of the hammer carries a head 32 arranged to strike the bottom wall of compartment 7 each time the free arm of the hammer is released after being raised, said free arm being tensioned to swing downwardly for that purpose. In this way, the occupants of the sunken vessel will be notified that the cable is being properly paid out to permit the float or marking buoy 9 to rise to the surface of the water.

Rigidly carried by the sunken vessel adjacent the compartment 7 and the bow of the vessel are hooks 33 or like grappling devices which may be readily engaged by a further grappling device or hook 34 when the latter is lowered from a rescue vessel 35 adjacent the point where the float or marker 9 is found floating on the surface of the water. In this way, the raising and salvaging of the sunken vessel is facilitated.

In operation, the cover is opened in the event of the vessel sinking. This is effected by the spring device 25 when the latch-hook 17 is released, or should the device 25 fail, the cover may be started by operating the shaft 24 and raising the rack-bar 22. Upon opening of the cover, the float 9 is released and

rises to the surface of the water and the cable 11 pays out, the cable unwinding from and turning the drum so as to operate the hammer 28 and notify the occupants that the apparatus is functioning properly. When the salvaging vessel 35 locates the float 9, the grappling member 34 is lowered adjacent thereto, and by proper maneuvering, is engaged with one of the grappling devices 33. The device 34 being associated with hoisting apparatus on the rescue vessel, the sunken vessel may then be readily raised to salvage life and property on the same.

Minor changes are contemplated within the spirit and scope of the invention as claimed.

What I claim as new is:

1. In a device of the class described, a compartment having a drum and a float therein, a cable connecting the float and drum and wound on the latter, a spring hammer mounted on and arranged and tensioned to strike the bottom of said compartment, and means operatively connecting the drum and hammer for intermittently raising and releasing the latter as the drum is rotated by paying out the cable therefrom.

2. In a device of the class described, a compartment having a drum and a float therein, a cable connecting the float and drum and wound on the latter, a spring hammer mounted on and arranged and tensioned to strike the bottom of said compartment, and means operatively connecting the drum and hammer for intermittently raising and releasing the latter as the drum is rotated by paying out the cable therefrom, said last named means comprising a shaft for the drum having a lateral arm and a lateral extension on the hammer arranged in the path of said lateral arm.

3. In a device of the class described, a compartment having a float therein, a cable connecting the float and compartment, a cover for said compartment, means to releasably hold said cover closed, and a supporting member yieldably suspended in said compartment and having the float disposed thereon, the suspending means for said supporting member being adapted to be placed under tension when the cover is closed for forcibly projecting the float from the compartment when the cover is opened.

4. In a device of the class described, a compartment having a float therein, a cable connecting the float and compartment, a cover for said compartment, means to releasably hold said cover closed, and a supporting member yieldably suspended in said compartment and having the float disposed thereon, the suspending means for said supporting member being adapted to be placed under tension when the cover is closed for forcibly projecting the float from the compartment when the cover is opened, and

means including a manually operable vertically movable rack-bar bearing on the under side of said cover for starting the latter open.

- 5 5. In a device of the class described, a compartment having a float therein, a cable connecting the float and compartment, a cover for said compartment, means to releasably hold said cover closed, and a supporting member yieldably suspended in said compartment and having the float disposed thereon, the suspending means for said supporting member being adapted to be placed under tension when the cover is closed for 10 forcibly projecting the float from the compartment when the cover is opened, and means including a manually operable vertically movable rack-bar bearing on the under side of said cover for starting the latter 15 open, and a spring device having a free arm bearing against the under side of said cover to assist and complete opening of said cover.

20 In testimony whereof I affix my signature.

25 GHOUGAS ZAHRAJIAN.
